UNITED STATES PATENT OFFICE.

REINHOLD A. NORLING, OF AURORA, ILLINOIS, ASSIGNOR TO AURORA AUTOMATIC MACHINERY COMPANY, OF AURORA, ILLINOIS, A CORPORATION OF ILLINOIS.

TRANSMISSION-GEARING.

1,142,357.

Specification of Letters Patent.

Patented June 8, 1915.

Application filed September 18, 1913. Serial No. 790,578.

To all whom it may concern:

Be it known that I, REINHOLD A. NORLING, a citizen of the United States, and a resident of Aurora, in the county of Kane and State of Illinois, have invented certain new and useful Improvements in Transmission-Gearing; and I do hereby declare that the following is a full, clear, and exact description thereof, reference being had to the accompanying drawings, and to the letters of reference marked thereon, which form a part of this specification.

This invention relates to improvements in power transmission mechanism, and more particularly to transmission gearing adapted for use in the construction of power operated drills, and like implements of portable character.

My invention embodies a construction and arrangement of power transmitting and speed reducing gearing to be adapted for use in a drill such as is fully described and illustrated in an application for Letters Patent filed simultaneously herewith to wit, on the eighteenth day of September, 1913, and bearing Serial Number 790,577.

My invention consists in the matters hereinafter described and more particularly pointed out in the appended claims.

In the drawings, Figure 1 is a view in longitudinal section of the electric drill embodying the features of my invention, Fig. 2 is an enlarged detail view in longitudinal section of the gear casing and parts mounted therein, Fig. 3 is a cross-sectional view taken on line 3-3 of Fig. 2, Fig. 4 is a cross-sectional view taken on line 4-4 of Fig. 2.

Referring to the construction shown in the accompanying drawings, the tool embracing a form of transmission gearing embodying the features of my invention comprises the several main parts as follows: A cylindric casing 1, containing the motor field coils, armature, brushes, brush holders, and a ventilating fan; a gear casing 2 supporting the tool spindle 3 and containing certain gears interposed between the motor armature shaft and the said tool spindle; a center plate or partition 4 between said motor casing 1 and gear casing 2 supporting suitable bearings for the gears, spindle, and armature shaft, and a handle 5 rigidly secured, by preference, to the motor casing 1, and containing a manually operable switch 6, and other suitable electrical connections. The motor

casing 1, center plate 4 and gear casing 3 are secured together by means of a plurality of cap screws 7 extending through lugs 1^a and 2^a formed on the adjacent edges of the motor and gear cases, respectively, and 60 through the edges of the center plate 4.

Referring more in detail to the construction of my device, the motor casing 1 is cylindrical in shape and preferably constructed of aluminum or similar light metal. 65 Within the central portion of the motor casing is supported the field coil 8, the same being held securely in place by means of longitudinal ribs 1^b formed on the inner surface of the casing 1, and a clamp screw 70 8^a extending through the lower part of the casing adjacent to the handle 5. Extending longitudinally in the motor casing is the armature comprising an armature shaft 9 upon which is mounted the armature core 75 10 and commutator 10^a. The said armature shaft 9 is rotatably mounted within the motor casing in the following manner: The rear portion of the said casing is provided with an outwardly extending, vertical 80 bridge member 11 integral with said casing and forming on either side comparatively large openings communicating with the interior of the casing. Within the central portion of the said bridge member is formed 85 an annular depression into which is fitted the outer anti-friction bearing 12 for the armature shaft. This bearing comprises two concentrically arranged collars or cage members 12^a and 12^b. The inner collar 12^a 90 is preferably pressed upon the reduced extremity of the armature shaft 9 and secured in position by means of a washer 13^a and a nut 13, the latter having screw-threaded engagement with the extremity of the said 95 shaft 9. The outer collar 12^b is loosely fitted within the depression formed within the bridge member in order to permit the desired end play of the armature shaft. Within the adjacent surfaces of the collars 100 12^a and 12^b are formed concentric grooves which form a bearing race for a plurality of anti-friction bearing balls 15. The inner extremity of the shaft 9 is provided with a partially threaded portion 9^a, upon which 105 is mounted a small pinion 16 having a diameter which is by preference substantially equal to that of the shaft so that in reality the same may form a continuation of the shaft having gear teeth cut on the end por- 110

tion thereof. The pinion 16 extends through an aperture 4^b in the center plate and projects beyond the same into the gear casing 2. An anti-friction bearing 17 supports the adjacent end of the shaft, and is retained within in a depression formed within the margin of the said aperture 4^b. This bearing is similar in construction to the bearing 11 hereinbefore described, and for that reason 10 the same need not be again described in detail. Furthermore, in view of the fact that I have used this type of anti-friction bearing in the construction of several parts of the device, the same in each case will henceforth be merely referred to as anti-friction bearings, and a detailed description of the same being omitted for the same reason indicated above. Immediately adjacent to the outer extremity of the armature shaft 9 and 20 constituting a part of the armature is the before mentioned commutator 10^a. Within the space surrounding the commutator are contained the brush ring 18 with the brush holders 19, 19, brushes and component parts 25 mounted thereon. The construction and arrangement of the brush mechanism is fully described and illustrated in my before mentioned copending application and hence a detailed description of the same is herein 30 purposely omitted.

Surrounding the entire end portion of the motor casing and including the bridge member 11, is a cup-shaped brush cover 22 of sheet metal. The margin of said cover 22 35 abuts against a shoulder formed upon the motor casing 1 by an annular flange 1^a upon the outer surface thereof, and is secured in position in the following manner: Immediately above and below the central portion 40 of the bridge member 11 are studs 23 and 24 which have screw-threaded engagement with the said bridge member. These studs extend through apertures in the brush cover, one of said studs 23 being of considerable 45 length and adapted to carry a feed handle 25 which screws upon the stud tightly against the cover. The other stud 24 is provided with a nut 26 also fitting against the cover. The central portion of the brush cover is 50 pressed outwardly to form a depression 22^a adapted to accommodate the extremity of the armature shaft 9 and nut 13. The portion of the brush cover adjacent to the depression 22^a bears against the collar 12^a of the anti-friction bearing and acts to hold the said collar in place. A suitable cover 27 55 is provided upon the portion of the brush cover forming the said depression and normally covers an oil hole extending through the brush cover. The brush cover is further 60 provided with a plurality of small holes 28 for the purpose of admitting air to the interior of the motor casing 1.

At the inner end of the interior space of 65 the motor casing is a fan 29, the same com-

prising a plurality of comparatively short fan blades 29^a, which move in an annular space in close proximity to the center plate and the wall of the motor casing. The hub 29^b of the fan is mounted upon the armature shaft by means of a pin 30 extending through the said hub and shaft. Within the wall of the motor casing is formed an annular channel 31 which surrounds the periphery of the fan. Communicating with the channel 31 and extending through the casing 1 are a plurality of annularly arranged holes (not shown) approximately surrounding the fan. The purpose of these holes is to form a means of disposing of air which is drawn through the motor casing by the fan, the air entering through the holes 28 of the brush cover and passing through the motor casing by means of the spaces formed between the field coils and the wall of the casing. The current of air induced by the fan carries away the heat generated by the motor thereby preventing the overheating of the same.

Referring now to the construction and arrangement of the gearing and spindle contained within and supported by the gear casing and center plate, and embodied in my invention: An internal gear spindle 32 is mounted within the gear casing and rotates 95 upon an axis lying parallel with and offset from the axis of the armature shaft. The said gear spindle is provided with an annular, cup-shaped portion 32^a, (Fig. 2), to the interior margin of which is fixed an internal gear 33. The said gear meshes with and is driven by the pinion 16 of the armature shaft 9. Adjacent to said internal gear and forming a part of said cup-shaped portion 32^a of the spindle 32 is a centrally arranged 100 depression 32^b, within which is retained an anti-friction bearing 34 similar in construction to the bearing 11 hereinbefore described. The outer collar 34^a of said bearing is held within said depression, and the inner collar 105 34^b is mounted in a stationary position in the following manner: The center plate 4 is provided with a boss 35 in axial alinement with the internal gear spindle and projects a short distance into the cup-shaped portion 110 32^a thereof. The said boss 35 securely holds a cylindric spindle-supporting bearing member or guide 36 within a central bore thereof, said guide being preferably of the form of a stub shaft one end of which projects into 115 the depression 32^b, and the opposite end of which is supported in the said bore of the boss 35. The guide is further provided with an annular peripheral flange or collar 36^a at the central portion thereof which 120 abuts against the face of the boss 35 and which acts as a retainer for the bearing 34 and also serves to prevent the longitudinal movement of the guide in a direction away 125 from the tool spindle. Upon the outer end 130

- of said guide is tightly pressed the inner collar 34^b of the anti-friction bearing 34. The remaining integral portion of the internal gear spindle 32 comprises a stub shaft 5 32^c which terminates adjacent to the end wall 2^a of the gear casing, there being provided at that point an anti-friction bearing 37 of the before described construction, the inner collar member 37^a being fixed to the 10 extremity of the said stub shaft portion of the internal gear spindle, and the outer collar 37^b, by preference, loosely mounted with an annular seat formed within the casing adjacent to the said end wall of the same. 15 Rigidly mounted upon said stub shaft portion 32^c of the gear spindle 32 and adjacent to the cup-shaped portion 32^a thereof, is a gear wheel or pinion 38, secured by means of a nut and washer 39 and 40, respectively, 20 the said nut engaging a threaded portion of the stub shaft 32^c lying between the said pinion 38 and the bearing 37. 25 Extending parallel with the internal gear spindle in the hereinbefore mentioned tool spindle 3, its axis being likewise parallel to the axis of the armature shaft and offset therefrom in the opposite direction from the axis of the internal gear spindle. The spindle proper consists of a hollow shaft 30 having at its inner end an enlarged cylindric portion having the form of an annular flange 3^a which surrounds a centrally disposed annular cavity. Upon the outer surface of, and in concentric relation to, this 35 flange 3^a is mounted the spindle gear 41 the same being preferably pressed on to an annular bearing surface upon the periphery of the flange or hollowed out portion 3^a of the tool spindle 3 and retained in position by means of an annular shoulder 3^b. The 40 said spindle gear meshes with the pinion 38 mounted upon the stub shaft portion 32^c of the internal gear spindle 32. The said spindle gear 41 and pinion 38 are 45 mounted upon their respective bearings so that they may be readily removed and a different sized gear and pinion substituted. In this way the ratio of the gears may be changed to effect a greater or less speed of 50 the drill spindle as described. The drill spindle 3 is rotatably mounted within the gear casing by means of bearings arranged in the following manner: Within the outer portion of the cavity formed by the annular collar 3^a is located a roller bearing 42, 55 comprising a plurality of cylindric rollers 42^a loosely retained within a cage 42^b. The said roller bearing is interposed and bears upon the elements as follows: A bushing 60 43 is fitted tightly to the flange 3^a and surrounds the bearing forming an outer bearing surface for the roller 42^a. The inner bearing surface of the roller engages a cylindric bearing guide or stub-shaft 44 65 similar in form and function to the guide 36. The said guide 44 projects a short distance into the cavity of the tool spindle and is supported by means of a boss 45 integral with the center plate 4 and having a central bore into which extends a portion 70 of the said guide. The guide 44 is further provided with an annular flange 44^a bearing against the face of the boss 45. Within the said cavity of the tool spindle and adjacent to the roller bearing is a thrust bearing comprising parts as follows: A ball race 46 fits tightly within the inner extremity of the cavity formed by the flange 3^a of the tool spindle 3 and comprises a 75 circular plate provided with a concentric groove within which are retained a plurality of bearing balls 47. These balls 47 are interposed between said ball race 46 and a circular thrust plate 48 loosely mounted within the cavity and which plate abuts 80 against the end face of the guide 44. By this construction the thrust bearing acts to transmit the end thrust of the tool spindle to the guide 44 and in so doing diminishes the friction resulting from the endwise 85 force exerted by the spindle during the operation of the drill or other tool carried in the spindle. The tool spindle is further provided with an external roller bearing 49 (Fig. 2), surrounding the same at substantially its central portion and between the annular flanged portion 3^a of the spindle and the end wall 2^a of the casing 2. This 90 roller bearing is of the usual construction comprising rollers 50 surrounding the shaft 95 and bearing against bushings 51 and 52 secured to the surface of the spindle and within a similar slot formed in the wall of the casing 2, respectively, and roller thrust plates or rings 53 against which the ends 100 of the rollers abut and which are interposed between the ends of said rollers and the shoulder 3^b of the spindle and the end wall 105 of the casing 2^a. The tool spindle projects through an aperture formed in the end wall 110 of the gear casing, there being provided at that point a stuffing box 54, which has screw-threaded engagement with the inner surface of an annular flange 2^b projecting outwardly from the end wall 2^a and surrounding the aperture therein through which the tool spindle extends. Within a bore formed at the inner end of said stuffing box is retained a packing 55 of suitable material, provided for the purpose of preventing the escape of lubricating oil from the interior of the said casing 2. A central bore or socket extends through the outer portion of the spindle and communicates with the cavity of its inner end. The said 120 socket is of a uniform diameter and is provided at its inner end with a plurality of longitudinally extending and diametrically arranged inwardly projecting ribs or projections 3^c. This central bore or socket is 125 130

adapted to hold the drill chuck 57, within the jaws 57^a of which is tightly held the drill or similar tool. The chuck 57 is provided with a shank 58 adapted to fit snugly 5 within the said socket of the drill spindle and terminates at a short distance from the ball race 48 of the thrust bearing. The said shank is provided at its extremity with longitudinal grooves 58^a adapted to engage 10 the ribs 3^c to prevent the relative rotation of said shank within the drill spindle. In order to retain the drill chuck in its socket, the following means are provided: Upon the outer end of the drill spindle is mounted 15 a locking nut 60 having screw-threaded engagement with the threaded extremity of the said spindle. The shank of the drill chuck is provided with an annular flange 58^b against which the lock-nut bears, thus 20 by tightening the lock-nut upon the said flange the chuck is held in place. The flange 58^a also acts to limit the distance which the shank of the chuck may enter the drill spindle socket.

25 Extending at right angles to the longitudinal axis of the motor casing, is a hollow cylindrical extension 1^d integral with said motor casing. The said extension is provided with a circular marginal flange to 30 which is rigidly secured the before mentioned tool handle 5, the same also extending at right angles to the axis of the motor casing. The handle comprises a tubular member having two cup-shaped extremities and 35 a smaller intermediate central portion serving as a grip for the hand of the operator. At the upper extremity of the handle is provided a flange 5^a, registering with the flange of the extension 1^d of the motor casing and through which extends cap-screws 61, 61, by means of which the said handle is secured to the motor casing. Within the handle 5 and adjacent portion of the extension 1^d, are contained the switch 6 and 40 connections. The said switch is preferably of the form and construction fully described and illustrated in my co-pending application and hence will not be herein described.

45 Within the lower cup-shaped portion of the handle is an electrical connection or socket 62 connected with the switch 6 by means of the conductor wires 63. The said connection block 62 is adapted to receive a suitable plug attached to a sufficient length 55 of wire whereby electric current may be supplied to operate the device.

50 By the construction of an electric drill herein described and illustrated, and more particularly by the construction, and arrangement of the gearing embodied in my invention, several advantageous results are obtained, among which may be mentioned the ease and convenience with which the parts may be reached and removed when it 55 is desired to renew or replace broken or

worn parts; the compact manner in which the rotating parts are mounted, and the novel and efficient manner of providing bearings for the said rotating parts.

One advantage of particular importance 70 is the form of bearings used in connection with the internal gear and the drill spindle, consisting of the stationary guides 36 and 44 secured to the center plate, and the anti-friction bearings mounted upon them. This construction not only permits the external gear and drill spindle to have adequate bearings to afford the least loss of power by friction, but makes it possible to locate bearings which are a sufficient distance apart 75 to accurately center and brace the spindle entirely within the gear and spindle, the result being that the most light and compact arrangement is obtained, whereby the size of the gear casing is materially reduced, 80 the extra weight of bearings likewise materially reduced, and the highest possible degree of efficiency is obtained. The gear case is easy of access, so that the gear wheel 85 39 and pinion 37 may be removed and others substituted if a change in the gear ratio is desired. Furthermore, the interposing of the internal gear spindle between the armature shaft and the tool spindle enables a considerable reduction of speed to be obtained thereby permitting the use of a high speed motor, yet the speed of rotation of the tool spindle is sufficiently low to insure the proper operation of the tool. Again, the spindle gear 41 and pinion 38 of the gear 90 100 spindle 32 being removable, the same may be easily replaced by gear wheels and pinions of various ratios as already suggested, thus the speed of rotation of the tool spindle can be easily changed as the various classes of 105 work may require.

Further features of construction embodied in the form of drill herein described and illustrated, constitutes the subject matter of the before mentioned co-pending application. 110

I am aware that the construction and arrangement of the power transmitting mechanism embodying my invention may be variously modified without departing from the 115 spirit of my invention, and for that reason I do not wish to be limited to the specific construction herein described and illustrated in the accompanying drawings, except in so far as it is specifically pointed out in the 120 appended claims.

I claim as my invention:

1. The combination of a driving member, a driven member provided with a gear wheel, a rotative gear spindle parallel with 125 said driven member and in operative connection with said driving member, said gear spindle being provided at one end with an annular depression, a pinion mounted on said gear spindle intermediate of said de- 130

pression and the other end of said gear spindle, said pinion meshing with the gear wheel of the driven member, a fixed cylindric bearing guide projecting into said depression, and an anti-friction bearing retained in said depression and supported by said bearing guide.

2. The combination of a driving member provided with a pinion, a rotative driven member, a gear spindle in parallel and offset relation to the axis of said driving member, said driven member and gear spindle being provided with intermeshing gear wheels and at their adjacent ends with cylindric shaped 15 depressions, fixed cylindric bearing guides in axial alinement with said driven member and gear spindle and projecting into said depressions, anti-friction bearings mounted in said depressions and supported by said bearing guides, and a gear member upon said gear spindle located outwardly beyond the depression thereof and meshing with the pinion of said driving member.

3. The combination of a driving member 25 provided with a pinion, a rotative driven member, a gear spindle in a parallel offset relation to the axis of the driving member, intermeshing gear wheels upon said driven member and gear spindle, the same being 30 provided with annular depressions at their adjacent ends, fixed bearing guides in axial alinement with said driven member and gear spindles and projecting into said depressions, anti-friction bearing members mounted 35 in said depressions and supported by said bearing guides, and an internal gear wheel upon the marginal portion of the recess of said gear spindle and located outwardly beyond the adjacent bearing member, said internal gear wheel meshing with the pinion of said driving member.

4. The combination of a driving member

provided with a pinion, a rotative driven member provided with a gear wheel, a rotative gear spindle comprising an endwise 45 opening cup-shaped portion at one end thereof, a stub shaft integral therewith, an internal gear secured to the marginal portion of said cup-shaped portion and meshing with said driving pinion, a central depression formed in said cup-shaped portion immediately inward from said internal gear wheel, a fixed cylindric bearing guide projecting into said depression, an anti-friction bearing in said depression and supported 50 upon said bearing guide, an anti-friction bearing at the end of said stub shaft, and a pinion removably mounted upon said stub shaft meshing with the said gear wheel of the driven member.

5. The combination of a driving member provided with a pinion, a rotative driven member, a gear wheel removably secured to said driven member, a rotative gear spindle parallel with said driven member, the same 55 comprising an endwise opening cup-shaped portion and a stub shaft integral therewith, an internal gear mounted upon the marginal portion of said cup-shaped portion, an anti-friction bearing retained in the inner portion of said cup-shaped portion, a pinion removably mounted on said stub shaft and meshing with said gear wheel of the driven member, and a fixed cylindric bearing guide projecting into said cup-shaped portion and supporting said anti-friction bearing.

In testimony, that I claim the foregoing as my invention I affix my signature in the presence of two witnesses, this 4th day of September A. D. 1913.

REINHOLD A. NORLING.
